MULTIPLE ELECTRODE DISCHARGE
TUBE ENERGIZING

Benjamin F. Miessner, Short Hills, N. J., assignor,
by mesne assignments, to Radio Corporation of
America, New York, N. Y., a corporation of
Delaware

Application September 18, 1929, Serial No. 393,387
Renewed January 27, 1934

17 Claims. (Cl. 250—27)

My invention relates to energizing multiple electrode electron discharge tubes and like space discharge devices for operation from unsteady sources of current energy so as to limit, control, or neutralize the effects of the unsteady current energizing, and in particular to avoid hum production in systems employing such tubes for amplifying sound representing currents, radio broadcast receivers and electrical phonographic reproducers in particular being contemplated.

My present invention relates to the control of the various phenomena accompanying the operation of the system disclosed in Fig. 3 of my copending application Serial Number 360,045 filed May 3, 1929, with varied constants and circuit connections, and includes modifications thereof, so that this application is a continuation in part of my application hereinbefore mentioned.

My present invention has for a particular object hum current suppression or control in the output circuit of a vacuum tube with the aid of an auxiliary electrode, such as an electrode positioned between the cathode and anode and controlling the potential of the auxiliary electrode relative to the cathode in two respects, namely, with respect to the direct current component of a fluctuating unidirectional energizing source, and with respect to the fluctuating current component of said source.

Another object is the suppression or control of carrier current modulation in so-called radio frequency amplifiers arising from energizing the electrodes of the tubes of such amplifiers from unsteady sources of current.

My invention is particularly applicable to systems employing the so-called "shielded-grid" type of tube having the electrodes energized with energy derived from an alternating current source of supply.

Other objects and features of my present invention will be apparent from the following description and explanation in connection with the figures of the accompanying drawings in which like reference characters designate like elements so far as possible in the several figures in which:

Fig. 1 diagrammatically illustrates a four element electron discharge tube of the so-called shielded grid type connected in a system for describing and explaining the effects of the energization of the electrodes of the tube in accordance with the principles of my invention, and particularly suited for analyzing the effects within the tube when the anode or plate thereof is energized by fluctuating potentials while the shielding electrode is energized either from a source

of non-fluctuating potential or from a source of fluctuating potential similar to the plate energization.

Fig. 2 diagrammatically illustrates a system utilizing features of Fig. 1 and wherein the tube VT is used as a filter device similar to the use of the tube described in my copending application Serial Number 360,042 filed May 3, 1929.

Fig. 3 diagrammatically illustrates another system utilizing features of Fig. 1 in which the load upon the source of fluctuating current is reduced to a minimum by the omission of loss-resistors, and including distribution of filtering devices within the system where needed, the basis for which two features may be found in my copending application Serial Number 117,076, filed June 19, 1926.

Fig. 4 illustrates a modification of the system of Fig. 3 wherein residual fluctuations derived from the plate current of the tube are impressed upon the input circuit thereof of such phase and intensity to oppose, for obliteration if desired, any hum currents tending to pass through the output transformer.

Fig. 5 diagrammatically illustrates the system of Fig. 3 energized by the system of Fig. 2 and wherein the arrangement constitutes two stages of amplification in cascade, one stage acting as an output stage and also as a filter system for the preceding stage of amplification, similar to 30 the arrangement illustrated and described in Fig. 2 of my copending application 360,042 hereinbefore mentioned.

Figs. 6, 7, 8, 9 and 11 are graphs illustrating the logical development of a theoretical basis for the present invention.

Fig. 10 is a modification of the system shown in Fig. 4.

Referring to Figs. 1 to 5 SF indicates a source of fluctuating unidirectional current, shown in Fig. 1 with the usual conventional details for deriving such current from an alternating current source, and conventionally in Figs. 2 to 5. The negative and positive terminals 1, 2 respectively, are shown shunted by the usual storage and filter condenser C₁, which may be followed by additional filter elements of well-known selection and arrangement if desired. VT is shown for example as the four electrode so-called shielded-grid type of tube, a commercial type 324 for example, which may have a unipotential cathode K maintained at effective electron emission temperature by heating the element H with alternating current supplied through a transformer HT. The plate electrode of each tube is energized by 55

connection to the positive terminal 2 of source SF.

In the systems of Figs. 1, 3, 4 and 5, I have provided a resistance R connected between the cathode K and the negative terminal 1 of source SF 5 for developing the usually required negative grid potential, the grid G of each tube being connected to a point in R more negative than cathode K through an input system, for example a transformer T₁ suitable for the current frequencies 10 being handled. The resistance R may be bypassed by the usual signal current by-pass condenser C₂. Each of the systems is provided with an output transformer T₂ suitable for the frequency of the currents being handled, though 15 input and output elements other than transformers may be employed as is well known.

In the arrangement of Fig. 1, I have shown various switches for arriving at selected circuit connections and selected modes of energizing the 20 cold electrodes of the tube VT to facilitate explaining the features of my invention in connection with effects had and graphic representations of them. The battery B₁ with associated potentiometer P₃ provides for impressing any desired 25 degree of steady potential of auxiliary electrode G' through switch SW₂, and the potentiometer P₂ across the fluctuating current course permits of substituting a fluctuating potential for the steady battery potential. The potentiometer P₁ 30 permits of energizing the plate electrode P with any desired degree of fluctuating potential. The switch SW₁ permits of introducing or removing a resistance R₁ of any desired value from a series 35 relation with auxiliary electrode G'. Switch SW₃ permits of connecting a condenser C₃ of any desired value between the auxiliary electrode G' and either the cathode K or the negative terminal 1 of the source. Switch SW₄ provides for short-circuiting or removing any effects of potential in resistance R from grid electrode G. 40

In general practice with amplifying tubes energized from alternating current sources it is desirable to materially diminish, or to limit and control in specific manner, the fluctuating current 45 component derived from such energizing appearing across transformer T₂ or other output element if acceptable hum reduction is to be had. By pointing out different connections possible in Fig. 1 and the results had as shown in the graphs 50 of Figs. 6, 7, 8 and 9, I believe I develop logically a theoretical basis for an understanding of my present invention.

With switch SW₄ closed to remove potential effects from the grid G, plate P and auxiliary electrode G' energizing effects can be examined independently of grid potential effects. Now the battery B₁ steadily maintaining G' at a usual operating potential of approximately 50 volts through left hand closure of switch SW₂, and 55 switches SW₁ and SW₃ being open or closed as not affecting direct current energizing, obviously no hum current production arises from auxiliary electrode energizing, thus leaving the arrangement in condition for investigating the hum current production arising from plate electrode P's energizing with fluctuating current through potentiometer P₁, and this is shown in the graphs 60 of Fig. 6 as representative of one set of measurements made by me when employing a source of fluctuating potential having an average direct current potential of 220 volts between terminals 1 and 2 and a severe fluctuating component of 20 volts.

Thus connected and energized the average plate

current changed as shown in graph I_p of Fig. 6 as the plate potential was changed as indicated by the abscissae scale. Voltmeter readings of equivalent hum current volts in indicator HI produced the hum graph E_h of Fig. 6 with the 5 changing of plate potential.

Analyzing these graphs it is seen that in that region where the plate current graph is steep the hum production is severe, but falls off materially beyond the indicated point O of plate 10 current saturation, becoming in fact most reasonably low as the plate current graph flattens out. In other words, as far as hum production arising in plate energizing with fluctuating current is concerned, the proper point of operation 15 for materially reducing hum is beyond the origin of saturation O.

The next step investigates the effect had by energizing the auxiliary electrode G' with the same fluctuating potential by connecting switch 20 SW₂ to potentiometer P₂ to give approximately 50 volts as before, switch SW₁ to eliminate resistance R₁ and switch SW₃ open to eliminate condenser C₃, switch SW₄ still being closed.

The result is shown in the graphs of Fig. 7, 25 the hum graph E_h showing that the hum current in indicator HI increases rapidly at the steep part of the plate current graph I_p, and remains at a slightly increasing large value beyond the origin of saturation O, substantially the same configuration as the plate current graph. Comparing with the graphs of Fig. 6, it is seen that a fluctuating potential on the auxiliary electrode has an effect 30 on hum production many times more troublesome than such a potential on the plate when beyond saturation. I also point out that in the region indicated by the dotted portion x to y of graph E_h of Fig. 7 there is noted a decided tendency 35 towards instability analogous to high frequency oscillation due to so-called dynatron effect. 40

These considerations therefore point out the particular desirability of materially reducing the effect of energizing the auxiliary electrode G' with fluctuating potential current, and I have found that the usual system permits of accomplishing 45 this in a simple and effective manner. Usually the potential of the source SF for the plate electrode is much in excess of that needed for the auxiliary electrode, so that an excess potential selected from potentiometer P₂, or even from the 50 positive terminal 2, can be reduced by the loss of potential in a high resistance R₁ had when switch SW₁ is open or eliminating it entirely. Selecting a definite value of resistance R₁ for a given potential from P₂ will result in the desired 55 operating potential on G' as determined by the space current flow from cathode K to auxiliary electrode G', and with the usual high potential of source SF for the plate electrode the resistance R₁ can be made high; that is, of the order of 60 100,000 ohms to produce the desired lowering of potential on G'.

This order of high resistance is particularly suitable for co-operating with a suitable value condenser C₃, as by closing switch SW₃, for most effectively filtering the usual 60 or 120 cycle fluctuating current originating in source SF from rectified commercial alternating current, thereby materially reducing the fluctuating potential component on auxiliary electrode G', even though 70 the filtration of the fluctuating current at the source SF is most incomplete.

The effect of this high order of filtration of the energy applied to electrode G' in company with normal fluctuating energy applied to the plate 75

electrode is shown in the graphs of Fig. 9, switch SW₄ still being closed to eliminate grid effects. As before graph I_p shows the plate current with change of plate potential, the potential of electrode G' being maintained unchanged. Graph E_h represents the degree of hum current for various values of plate potential as observed in indicator HI, and shows a most favorable low degree of hum beyond origin of saturation O.

10 While the preceding considerations provide for definite steps of improvement, further benefits can be had by bringing into cooperation grid effects. With switch SW₄ open so that fluctuations passing through grid biasing resistance R are impressed on grid G, the graphs of Fig. 8 illustrate these effects. With switch SW₃ closed to the right so that fluctuating current components passing through condenser C₃ do not pass through resistance R to effect fluctuating potential on grid G hum improves with increase of capacity of condenser C₃ as shown by graph a, which is substantially linear, indicating that the improvement is due to improved filtration of the fluctuating component or auxiliary electrode G' almost entirely.

With switch SW₃ closed to the left, so that fluctuating current passing through condenser C₃ also passes through resistance R to affect grid G, graph b of Fig. 8 shows the resulting hum change with 30 change of value of condenser C₃. Here the hum falls off sharply with increase of capacity of C₃, becoming a minimum in the particular arrangement investigated with a capacity of C₃ substantially .3 microfarads, and increasing thereafter. 35 This therefore shows that a controlled amount of hum feed-back is useful to oppose by grid effects the hum arising from energizing the plate and auxiliary electrodes from fluctuating potential sources. The plate and auxiliary electrode effects 40 are in the same phase, so that they cannot be used one against the other for neutralizing effect.

I also point out that the use of a high resistance R₁ in series with the auxiliary electrode has the benefit of eliminating the unstable condition indicated from x to y in graph E_h of Fig. 7 previously mentioned.

Fig. 2 shows one arrangement for employing some of the features of my invention outlined in connection with Fig. 1. Four electrode tube VT 50 is energized from the fluctuating and poorly filtered output of source SF. All loss-resistors are eliminated to lessen current drain on the source and filter, thereby having best filtration possible for the filter material used. The reduced potential of auxiliary electrode G' is obtained by lowering the potential of the source through high resistance R₁ series connected, the filter condenser C₃ being connected between electrode G' and cathode K as previously described. The grid G 55 and cathode K are tied together.

With this arrangement of Fig. 2 the potential developed across load resistance LR, shunted by by-pass condenser BC, is substantially steady as shown by graph E_h in Fig. 9, so that this system 60 may be used in lieu of the system shown in Fig. 1 of my copending application Serial Number 360,042 filed May 3, 1929 for the energization of the space discharge paths of other tubes of a radio receiving system or any other device in which a unidirectional current of steady potential is desired.

Fig. 3 illustrates the hum feed-back system described with reference to Fig. 1 with the additional feature that in this instance the load of the 75 loss resistor has been removed from the filter cir-

cuit and the electrode G' is energized directly from the positive terminal 2 of the source SF. This arrangement shown in Figs. 2 and 3 permits of appreciable reduction of the values of the elements of the filter system to such an extent that 5 a single condenser of a value of approximately 2 microfarads shunting the output of a full wave rectifier constitutes a sufficient filter system in many instances.

Figure 4 diagrammatically illustrates another 10 system specifically described with reference to Fig. 1 with the added feature that condenser C₅ is utilized as a hum feed-back control. The use of such a condenser has been described in detail with reference to a three element tube in my co-pending application Serial Number 251,807 filed Feb. 4, 1926 and this circuit arrangement is substantially the same as that of Fig. 3 of my co-pending application Serial Number 360,045 filed May 3, 1929. 20

Summarizing briefly, condenser C₅ of Fig. 4 shunts a portion of the hum currents from the space discharge path of the tube directly to resistance R, and permits by selection of capacity values developing hum potentials across resistance R in 25 the grid-filament circuit of the tube of such phase and amplitude that the effect on the grid G is controlled to most effectively commutate from the space discharge path of the tube any hum currents tending to develop therein by reason of the fluctuating potential upon the plate and auxiliary electrodes. 30

Fig. 5 diagrammatically illustrates a tube VT₁ associated with circuits in the manner of Fig. 3 energized through a tube system like that of Fig. 2 35 including a tube VT₂, with the additional feature that the tube VT₂ is utilized also as a stage of amplification succeeding the tube VT₁. In this arrangement the signal input of the system is through the transformer T₁, and the output of the 40 system is through the transformer condenser system TC, the grid-filament circuit of tube VT₂ being coupled to the plate circuit of tube VT₁ through the transformer T₂.

In Fig. 10, I have shown a modification of the 45 system of Fig. 4 in that I have provided condenser C₄ and resistance R₄ to function as a hum feed-back element for developing neutralizing potentials across the resistance R for grid G. In this arrangement I have provided switches SW₅ and SW₆ to enable a more clear understanding of the operating characteristics of this circuit as graphically illustrated by the graphs of Fig. 11.

By way of example, with a tube of the 324 type, resistance R of 2000 ohms, a potential across condenser C₁ of 250 volts direct current having a fluctuating component of 20 volts, and switches SW₅ and SW₆ open, the resistance R₁ was varied between zero and 100,000 ohms to obtain the hum potentials in millivolts represented by graph A of 50 Fig. 11, a most excessive order of hum.

With switch SW₅ closed and a condenser at C₃ of .25 microfarads, the graph B of Fig. 11 graphically illustrates the hum in millivolts as the resistance R₁ varied between zero and 100,000 ohms. 55

Comparison of graphs A and B with the aid of the hum millivolt ordinates at the left of Fig. 11 shows the effectiveness of filtration in the auxiliary electrode circuit on hum reduction.

Further, closing switch SW₆ and for each value 70 of R₁ adjusting R₄ and C₄ to a point of minimum hum, along with the above value of filter condenser C₃, graph C of Fig. 11, drawn to the greatly enlarged scale of ordinates on the right of Fig. 11, graphically illustrates the hum in millivolts as the 75

resistance R_1 is varied between zero and 100,000 ohms.

A comparison of graphs B, using ordinates at the left of the figure, shows the effectiveness of selected hum feed-back control in such a circuit. A comparison of graphs A, ordinates at left, and C ordinates at right, shows the effectiveness of hum elimination when filtration and hum feed-back are combined, the importance of such comparison being overwhelming when it is considered that the fluctuating component of the potential across the output of the filter is substantially ten percent of the aggregate potential and the resultant hum is substantially one millivolt.

The systems shown and described are not only of value for the audio frequency portion of radio receivers when energizing a so-called all-electric radio receiver from commercial alternating current supply, but of great importance to the stages of radio frequency amplification as well.

It is well known that the energizing of tubes in the radio frequency portion from unsteady sources of potential results in modulation of the incoming high frequency carrier currents, and that variations in the plate circuits of such tubes are more effective than grid circuit variations, so-called "plate modulation" being generally used in preference to so-called "grid modulation" in transmitting systems for this reason.

The energizing modulation is effectively transferred with the carrier current from stage to stage to be finally liberated in the detector as a source of hum for amplification in the audio frequency portion of the receiver often developing a most disagreeable order of hum.

It is appreciated from graph B of Fig. 11 that mere effective filtration of the shielding grid circuit is most effective in reducing plate circuit hum variations, and since grid variations are not effective modulators, it in general suffices in treating radio frequency stages to rely on filtration without bringing in the vernier improvement of hum feed-back shown by graph C of Fig. 11. This refinement is particularly helpful in audio frequency stages followed by one or more stages of amplification.

Having described my invention with respect to several specific circuits and combinations thereof it is apparent that various modifications thereof may be made therein without departing from the spirit of my invention as defined in the claims appended hereto.

I claim:

1. In an electrical system, the combination of a source of unidirectional fluctuating current, an electron tube having a cathode, grid, auxiliary electrode and plate, means for energizing the space discharge paths of said tube between said cathode, grid and plate from said source, means for determining the direct current potential of said auxiliary electrode at a potential intermediate the direct current potentials of said cathode and plate electrode, means for reducing the fluctuating current component of the potential applied to said auxiliary electrode more nearly to the fluctuating component existing at said cathode, and means for impressing a predetermined amount of the fluctuating current potential of said source upon the grid of said tube of a phase to neutralize within said tube the effect of the fluctuating current energization of the electrodes of said tube.

2. In an electrical system, the combination of a source of unidirectional fluctuating current, an electron tube having a cathode, grid, auxiliary

electrode and plate, means for energizing the space discharge paths of said tube between said cathode, grid and plate from said source, means for determining the direct current potential of said auxiliary electrode at a potential intermediate the direct current potentials of said cathode and plate electrodes whereby said electron tube is operating at a point in the substantially flat portion of its plate current-plate potential curve, means for reducing the fluctuating current component of the potential applied to said auxiliary electrode more nearly to the fluctuating component existing at said cathode, and means for impressing a predetermined amount of the fluctuating current potential of said source upon the grid of said tube of a phase to neutralize within said tube the effect of the fluctuating current energization of the electrodes of said tube.

3. In an electrical system, the combination of a source of unidirectional fluctuating current, an electron tube having a cathode, grid, auxiliary electrode and plate, means for energizing the space discharge paths of said tube between said cathode, grid and plate from said source, means for determining the direct current potential of said auxiliary electrode at a potential intermediate the direct current potentials of said cathode and plate electrode, and means for reducing the fluctuating current component of the potential applied to said auxiliary electrode more nearly to the fluctuating component existing at said cathode, said means including a high impedance connection between said auxiliary electrode and said plate energizing means, and a connection between said auxiliary electrode and the cathode of said tube of low impedance to the fluctuating component of said source, and means for impressing a predetermined amount of the fluctuating current potential of said source upon the grid of said tube of a phase to neutralize within said tube the effect of the fluctuating current energization of the electrodes of said tube.

4. In an electrical system, the combination of a source of unidirectional fluctuating current, an electron tube having a cathode, grid, auxiliary electrode and plate, means for energizing the space discharge paths of said tube between said cathode, grid and plate from said source, means for determining the direct current potential of said auxiliary electrode at a potential intermediate the direct current potentials of said cathode and plate electrodes, means for reducing the fluctuating current component of the potential applied to said auxiliary electrode more nearly to the fluctuating component existing at said cathode, said means including a high impedance connection between said auxiliary electrode and said plate energizing means and a capacity connection between said auxiliary electrode and the cathode of said tube, said capacity connection being of low impedance to the fluctuating current component of said source, and means for impressing a predetermined amount of the fluctuating current potential of said source upon the grid of said tube of a phase to neutralize within said tube the effect of the fluctuating current energization of the electrodes of said tube.

5. In an electrical system, the combination of a source of unidirectional fluctuating current, an electron tube having a cathode, grid, auxiliary electrode and plate, means for energizing the space discharge paths of said tube between said cathode, grid and plate from said source, means for determining the direct current potential of said auxiliary electrode at a potential interme-

diate the direct current potentials of said cathode and plate electrode whereby said electron tube is operating at a point in the substantially flat portion of its plate current-plate potential curve, means for reducing the fluctuating current component of the potential applied to said auxiliary electrode more nearly to the fluctuating component existing at said cathode, said means including a high impedance connection between said auxiliary electrode and said plate energizing means and a capacity connection between said auxiliary electrode and the cathode of said tube, said capacity connection being of low impedance to the fluctuating current component of said source, and means for impressing a predetermined amount of the fluctuating current potential of said source upon the grid of said tube of a phase to neutralize within said tube the effect of the fluctuating current energization of the electrodes of said tube.

6. In an electrical system, the combination of a source of energy, an electron tube having a cathode, grid, auxiliary electrode and plate, means for energizing the space discharge paths of said tube between said cathode, grid and plate, a high impedance connection between said auxiliary electrode and one terminal of said source, a condenser connected between said auxiliary electrode and a point having a potential not greatly differing from the potential of the other terminal of said source, said impedance and condenser having such electrical dimensions as to constitute an effective filter for audio frequency currents, and means for impressing a fluctuating potential upon the grid of said tube of a phase to commutate out the fluctuating component of the plate current of said tube.

7. In an electrical system including an electron tube having a cathode, grid, auxiliary electrode and plate and connections for energizing the cathode plate discharge path of said tube from a source of unidirectional pulsating current, the method of eliminating fluctuations in the space current of said tube due to the fluctuating current energization which consists in energizing the auxiliary electrode with a substantially non-fluctuating potential of a value such that said tube operates at a point above the origin of saturation in the plate current plate potential curve of said tube and impressing upon the grid of said tube a fluctuating potential of such phase and amplitude as to substantially neutralize within said tube the residual fluctuations in the space discharge current of said tube.

55 8. In an electrical system, the combination of a source of energy in which there exists an undesired fluctuating component, an electron tube having a cathode, grid, auxiliary electrode and anode, means for energizing the space paths of said tube, a high impedance connection between said auxiliary electrode and one terminal of said source, a capacity connected between said auxiliary electrode and a point having a potential not greatly differing from the potential of the other terminal of said source, said impedance and capacity having such electrical dimensions as to constitute an effective filter for audio frequency currents, a biasing resistance connected between said cathode and grid, and means for shunting through said biasing resistance a portion of the undesired fluctuating component of such phase and magnitude that effects of the fluctuating component upon the tube are substantially neutralized.

75 9. In an electrical system the combination of

a source of energy in which there exists an undesired fluctuating component, an electron tube having a cathode, a grid, an auxiliary electrode and an anode, means comprising said source for energizing the space paths of the tube, a connection including a high impedance between the auxiliary electrode and one terminal of the source, a capacity connected between the auxiliary electrode and a point having a potential not greatly differing from the potential of the other terminal of the source, said impedance and capacity comprising virtually a shunt circuit across the source, the electrical dimensions of which are such as to simulate, in effect, an audio frequency by-pass circuit, a biasing impedance connected between the cathode and grid, an anode cathode circuit including said source and the biasing impedance in series, and means for impressing across the biasing resistance a portion of the undesired fluctuating component derived from the source in such phase and magnitude that the effects of the undesired fluctuating component upon the tube are minimized.

10. In an electrical system the combination of a source of unidirectional fluctuating current, an electronic tube including an indirectly heated cathode, a signal grid, an auxiliary grid and an anode, a connection from the signal grid to the negative side of said source including a coupling means, a connection from the negative side of said source to the cathode including a bias resistor, means including a coupling element connecting the anode to the positive side of said source, a connection from the positive side of said source to the cathode end of the bias resistor including an impedance and a condenser in series, a connection from the auxiliary electrode to the junction point of said serially arranged impedance and condenser circuit, said last named condenser being proportioned so that hum frequencies are transferred from the positive side of said source to the negative side of said source through the bias resistor and a by-pass condenser shunted across the bias resistor.

11. In an electrical system the combination of a source of energy, an electron tube having a cathode, a signal grid, an auxiliary electrode and an anode, means for energizing the space discharge paths of said tube between the cathode, grid and plate, a connection having a resistance of the order of 100,000 ohms between the auxiliary electrode and the positive side of said source, a connection including a variable condenser between the auxiliary electrode and the negative side of said source, said resistance and last named condenser being proportioned with respect to the fluctuating component of the source so that they form a shunt circuit across the source which acts, in effect, to by-pass hum frequencies from one side of the source to the other.

12. In a system as described in claim 11 in combination with said source of energy a filter circuit comprising at least a condenser shunted across the source for filtering out at least a portion of the fluctuating component of the energy from the source.

13. In an electrical system the combination of a source of unidirectional fluctuating current, a filter circuit connected to the output of said source comprising at least a condenser shunted across the source, a space discharge tube provided with a cathode, a signal grid, an auxiliary grid and an anode, means for energizing the space discharge paths of said tube between said cathode, grids and anode from said source, means for determining

the direct current potential of the auxiliary grid at a potential intermediate the direct current potentials of said cathode and anode, means for reducing the fluctuating current component of the 5 potential applied to said auxiliary grid more nearly to the fluctuating component existing at said cathode, said means comprising a connection between the auxiliary grid and the cathode for maintaining both thereof at substantially the 10 same alternating current potential, and means including the last named means for impressing a predetermined amount of the fluctuating current potential of said source upon the signal grid of said tube of a phase to neutralize within the tube 15 the effect of the fluctuating current energy of the electrodes of said tube.

14. In an electrical system the combination of a source of unidirectional fluctuating current a filter circuit therefor for filtering out a substantial portion of the fluctuating component of the current from said source, the output of the filter circuit including a negative and a positive terminal, an electron tube having a cathode, a grid, an auxiliary electrode and a plate, a connection from 25 the plate electrode to the positive terminal of the filter output including a coupling element, a connection including another coupling element from the grid of the tube to the negative terminal of the filter circuit, a bias resistor connected from 30 the negative terminal of the filter to the cathode of the tube, said bias resistor being included in both the grid circuit of the plate circuit of the tube, means for determining the direct current potential of the auxiliary electrode so that the 35 auxiliary electrode will be maintained at a potential intermediate the direct current potentials of the cathode and plate electrodes whereby said electron tube is constrained to operate at a point in the substantially flat portion of its 40 plate current, plate potential characteristic curve, means for reducing the fluctuating current component of the potential applied to the auxiliary electrode more nearly to the fluctuating component existing at said cathode comprising an 45 alternating current connection between the auxiliary electrode and the cathode and means including the last named means for impressing a predetermined amount of the fluctuating current 50 potential of said source upon the grid of the tube of phase and amplitude to neutralize within the

tube the effect of the fluctuating current energization of the electrodes of said tube.

15. A system as described in claim 14 wherein the last named means includes in addition to the alternating current connection between the auxiliary electrode and the cathode a path of high impedance connected between the plate and the auxiliary electrode. 5

16. In a system as described in claim 14 wherein said means for impressing a predetermined 10 amount of fluctuating current potential upon the grid of the tube includes in addition to the alternating current coupling between the auxiliary electrode and the cathode a resistor having a value of the order of 100,000 ohms connected between 15 the auxiliary electrode and the positive side of the source. 10

17. In an electrical network, a space discharge device provided with a cathode, a grid and an anode, energizing means for said device comprising a source of unidirectional current, said current having a fluctuating component, positive and negative terminals for said source, a connection including an impedance element between the negative terminal of the source and the cathode 20 of said device, a connection between the grid and cathode of said device, said last-named connection including energy transfer means and said impedance element, a connection including energy transfer means between the anode of said device 25 and the positive terminal of the source whereby said impedance acts to produce a bias potential for the grid of the space discharge device the magnitude of which is determined by the flow of current therethrough, a circuit connected between 30 the source side of the last-named energy transfer means and the cathode side of said impedance, said circuit forming in effect a by-pass path for at least a portion of the fluctuating component of said unidirectional current, the by-pass portion of 35 said current passing through said impedance thereby causing a fluctuating potential to be impressed upon the grid of the discharge device, said by-pass circuit including means to determine the magnitude and phase of the by-pass fluctuating 40 component so that the fluctuating potential impressed upon the grid of said discharge device will neutralize to any desired extent the remaining fluctuating component. 45

BENJAMIN F. MIESSNER. 50
